UNITED STATES PATENT OFFICE

2,242,089

MEANS FOR MAKING MINERAL WOOL

Charles F. Ramseyer, Chicago, Ill.

Application August 13, 1938, Serial No. 224,829

3 Claims. (CL. 49—53)

This invention relates to the production of mineral wool from coal ash slag, particularly as a by-product in the operation of wet-bottom coal fired boilers used for generating steam for heat and power purposes.

Heretofore, mineral wool usually has been produced commercially by melting argillaceous limestone or slags resulting from the smelting of various metallic ores with coke, but such mineral wools have been relatively expensive, due to the quarrying or handling of the raw material and the quantities of fuel required. Further, the mineral wool produced was not always uniform because of the lack of accurate control. The only method heretofore employed for controlling the temperature, viscosity and chemical content of the material has been by changing the ratio of rock or slag to the coke charge in the cupola, or by varying the composition of material added to the charge, and since in most plants it is a matter of hours before the materials charged in at the top of the cupola can influence the temperature or composition of the material coming from the tap hole, it will be seen that such control of the molten material and the mineral wool formed therefrom is very far from being either instantaneous or automatic.

In my copending application Serial No. 67,868, filed March 9, 1936, I have disclosed and claimed a novel method of and means of making mineral wool which includes a wet-bottom coal-fired boiler, which is an oxidizing furnace, and means for handling the fused coal ash slag as it comes from the boiler and maintaining the slag in the proper temperature and viscosity condition suitable for forming mineral wool, thus utilizing a waste material without previous value and producing a superior grade of mineral wool of uniform quality. One of the features materially contributing to the successful attainment of these results is the provision of a novel conditioning furnace construction, disclosed and claimed in my copending application, Serial No. 217,397, filed July 5, 1938, which receives the molten coal ash slag from the boiler and controls the temperature and viscosity of the slag so as to maintain the material in a state best adapted to facilitate the formation of mineral wool therefrom.

In the operation of a pulverized coal fired boiler of the "wet-bottom" or "slag-tap" type, the furnace temperature is kept high enough so that the ash of the coal collects on the floor of the furnace in a molten condition and can be drawn or tapped off at will. I have found, however, that frequent

ly there is considerable foaming and gassing at the tap hole, due to reactions resulting from slags of different compositions flowing from different parts of the furnace coming together at the

5 tap hole. Sulfur dioxide is the gas usually released as a result of these reactions and is present in the molten slag as small bubbles which make the slag stiff and non-fluid and interferes with the wool forming process and also with the operation of the conditioning furnace.

The object and general nature of this invention is the provision of means whereby the molten coal ash slag can be freed of all gases before it reaches the tap hole, whereby there is no tendency to

15 foam and gas when the slag is tapped off and led into the conditioning furnace. More specifically, it is a feature of this invention to provide a de-gassing zone in a boiler of the continuous slag tap type and hold the molten slag pooled in the

20 de-gassing zone of the continuous slag tap boiler until foaming has terminated, so that the molten slag will flow freely and readily into the conditioning furnace in a more or less steady stream, preferably while maintained at a relatively high

25 temperature to insure the continued fluidity of the de-gassed slag.

These and other objects and advantages of this invention will be apparent to those skilled in the art after a consideration of the following detailed 30 description of the preferred form of my invention.

In the drawings:

Figure 1 is a diagram of a boiler of the wet-bottom pulverized coal fired continuous slag tap type equipped with the present invention and particularly adapted to deliver molten slag to a conditioning furnace for bringing the slag to and maintaining it at the desired temperature and viscosity to facilitate the formation of mineral wool therefrom;

35 Figure 2 is a section, somewhat diagrammatically shown, taken along the line 2—2 of Figure 1, showing one form of slag pooling baffle;

Figure 3 is an enlarged vertical section taken generally along the line 3—3 of Figure 2, showing one means for heating the slag as it flows from the boiler slag spout;

Figure 4 is an enlarged section taken along the line 4—4 of Figure 3;

40 Figure 5 is a plan view, largely diagrammatic, of a modified form of slag pooling baffle;

Figure 6 is an enlarged section taken along the line 6—6 of Figure 5;

45 Figure 7 is an enlarged fragmentary plan view 50 of the slag baffle shown in Figures 5 and 6;

Figure 8 is an enlarged section taken along the line 8—8 of Figure 7; and

Figure 9 is a fragmentary view of the outer end of the baffle, being a view taken along the line 9—9 of Figure 7.

Referring first to the boiler shown in Figure 1, the furnace is indicated in its entirety by the reference numeral 1 and comprises suitable walls 2 of refractory material, which may be water cooled, as indicated by the upper headers 5 and 6 and the lower headers 7 and 8. Vertical grids connect the headers 5, 7 and 6, 8 so as to provide for the desired flow of cooling water to reduce the temperature of and protect the refractory material forming the side walls 2, as in the usual practice. The bottom of the furnace is indicated at 10 and is in the form of a relatively shallow trough having a slag opening 11. The bottom wall 10, like the side walls 2, is formed of refractory material and is cooled by a grid extending between the lower headers 7 and 8 and the inner headers 13 and 14. The steam generating unit of the boiler is indicated at 20 and has longitudinal tubes 21 and a cross drum 22, disposed above the combustion space C of the boiler 1.

The pulverized coal used for fuel is supplied through a conduit 25 to a pulverizing mill indicated at 26. Air is supplied for combustion from a draft fan (not shown) which forces air downwardly through a conduit 28, an air heater 29, and conduits 30 and 31 to a duct or wind box 32 from which the air flows through a duct 33 to a nozzle 34. Also, a branch duct 36 leads from the wind box 32 to the pulverizing mill 26, and a suction pipe 37 leads from the pulverizing mill to the inlet side of a blower 38. The latter draws air in through the pulverizing mill 26 and forces both the air and pulverized coal through a conduit 39 to an inner nozzle 40. From the space C the gases of combustion are passed over the boiler tubes 21 and through a breeching 42 and an economizer 43, and then through the air heater 29 to an induced gas fan (not shown) through a duct 44, from which they are released to atmosphere or otherwise disposed of.

According to the principles of the present invention the bottom 10 of the furnace is provided with a slag baffle indicated in its entirety by the reference numeral 50. The slag baffle consists of two sections 51 and 52 (Figure 2) disposed on opposite sides of the slag tap hole 11, and each section consists of a loop of pipe 54 having two lengths 55 and 56 connected together by a return bend 57 which is welded or otherwise secured to the inner end of the pipes 55 and 56. Bars of steel or other suitable material, indicated at 59, 60 and 61 in Figure 4, are welded with heavy beads to the pipes 55 and 56. A plurality of small pins 63 are welded to the upper bar 55 in diverging relation and are arranged to receive refractory material 64. The lower bars 61 of each baffle section are secured to the furnace floor in any suitable manner, and the bars 61 are protected by refractory material 65, as shown. Suitable conduits 67 and 68 are connected to the outer ends of the pipes 55 and 56 and extend outwardly through the boiler wall 2. Connections 69 and 71 are provided to receive pipes by which cooling water is passed through the baffle sections.

The flow of cooling water through the baffle sections 51 and 52 effectively protects them from the high temperature of the molten slag. As best shown in Figure 2, the baffle sections 51 and 52

10 extend a substantial distance along the furnace bottom and away from the slag hole 11, and the ends of the baffle sections 51 and 52 are turned inwardly, as 51a and 52a, the inturned ends being spaced apart by a small distance, indicated at 73.

15 The slag spout of the boiler 1 is best indicated in Figure 3 by the reference numeral 76 and consists of a passage 77 lined with suitable refractory. The lower portion of the spout may have a cooling water jacket 78 with suitable inlet and outlet connections, not shown. The outlet of the slag spout is indicated at 79 and has a port 80 adjacent which is a gas burner 81. Another gas burner 82 is provided adjacent the lower edge or legs 83 of the slag outlet 79. An opening 84 closed by a block 85 is formed in the outer portion of the spout 76 to provide for an inspection of the spout end when the block 85 is removed. The flames from the burners 81 and 82 keep the molten slag at the proper temperature and prevent it from freezing.

20 The conditioning furnace which receives the molten slag is indicated at 90, and for a more detailed description of this unit reference may be had to my copending application mentioned above. It will therefore suffice to state that the conditioning furnace comprises a suitable refractory container 91 supported on a frame 92 and provided with sets of water cooled electrodes 93 and 94 by which the temperature and viscosity of the molten charge in the furnace are maintained at the desired value. The furnace 90 is arranged for tilting about an axis so as to direct 25 a small flow of molten slag onto a suitable wool forming means, such as a spinning disc or jet of steam or air under pressure.

25 The molten slag from the furnace 1 is delivered to the conditioning furnace 90 through a slag runner indicated in its entirety by the reference numeral 100 and which includes a relatively stationary section 101 and a swingable section 102 disposed adjacent the furnace 1 and movable relative to the section 101 into and out of a position to receive the molten slag as it runs from the slag spout opening 79. Both runner sections 101 and 102 are made of refractory material and are generally hollow or tubular in form. Each runner section is provided with cooling coils indicated at 105 and 106, respectively, the latter being especially constructed to accommodate the swinging action of the runner section or diverting runner 102. Also, the runner sections are provided with suitable openings 30 establishing points of communication with the interior of the slag channel in the runner and heating means in the form of gas burners or the like are mounted at these points, indicated at 108 to 111, for maintaining the slag heated to the proper degree. The cooling coils 105 and 106 keep the runner 100 from getting too hot.

35 The purpose of heating the slag stream and, at the same time, cooling the slag runner, and also the slag spout 76 is, first, to keep the slag at a sufficiently high temperature, usually around 2500° F., so that it flows readily, and second, to keep the refractory at a sufficiently low temperature that it is not melted, dissolved or carried away by the molten slag. Usually the temperature of refractory should not exceed approximately 1700° F. Considering a temperature gradient line from the center of the slag stream to the cooling means, the cooling water being generally around 60° F., the point on the gradient line corresponding to 1700° F. deter-

mines the contour or surface of the runner, since if the slag is hotter, portions of the refractory will be melted down to a point where there is sufficient cooling to reduce the temperature to 1700° F., and if the slag is cooler then some of the slag freezes, itself becoming a part of the refractory and building up the latter to a point spaced inwardly of the cooling means and sufficiently close to the center of the molten slag that the temperature is 1700° F. It is to be understood that these values are merely illustrative.

In the operation of the boiler, the molten ash resulting from a combustion of the fuel collects on the side and bottom walls of the furnace and flows toward the slag hole 11. Due to the slightly different conditions in various parts of the furnace during operation, as mentioned above, the portions of molten slag coming from different parts of the furnace do not all have exactly the same chemical composition, and heretofore these different portions of molten ash did not meet or come together until just before or at the slag tap hole 11. This results in gassing and foaming at this point, since slags of different composition reacted with one another, generally to release sulphur gases. The molten slag became filled with tiny bubbles of gas which changed the consistency and characteristics of the slag and produced a material which did not flow readily.

According to the principles of the present invention, the baffle sections 51 and 52, with the small entrance opening 73, provide a construction in which all reactions between the slag portions from various parts of the boiler take place at a point well within the boiler where the temperature is high and the reactions thereby hastened. Hence, by the time the slag has reached the tap hole 11 all foaming and gassing has stopped and the slag flows as a free liquid with practically all gas removed. In other words, the baffle sections 51 and 52 set up or establish a de-gassing pool within the boiler, and the surface of pool defined by the baffles 51 and 52 is of sufficient extent that all reactions within the pool are completed before the molten slag reaches the slag spout and flows toward the conditioning furnace.

While in Figures 2 and 3 I have shown the de-gassing pool formed by the baffles as at one end of the boiler, it is to be understood that the de-gassing pool may be placed wherever desired or necessary. For example, it may be formed at one side of the boiler, as at or adjacent the right hand wall in Figure 1, if there should be any tendency for foam forming material to fall from the flames of the burners 40 into the de-gassing pool, which would be undesirable.

Another form of slag baffle is shown in Figures 5 to 9. In these figures the boiler is indicated at 1a and has walls 2a and a slag tap hole 11a in the bottom 10a of the boiler relatively closely adjacent a wall 3a. In this case the baffle, indicated in its entirety by the reference numeral 50a, is formed generally as a spiral so as to bring together the various slag streams from different parts of the furnace before they reach the slag tap hole 11a, thus affording a full opportunity for all gassing, foaming and other reactions between various portions of the molten ash to take place before the slag reaches the tap hole 11a.

In this form of the invention, the slag tap hole 11a is surrounded by a ring 120 which consists of a number of loops, preferably three, of pipe 121, the upper of which enters a water-cooled

spout 123, and the other two of which, as indicated at 126, are placed in a position closely adjacent the furnace floor 10a so as to provide a lip 126 over which the slag within the baffle 50a flows through the slag tap hole 11a. The pipe loops 121 are provided with bars 128, 129, and 130 which are coextensive with the pipes 121 and are securely welded or otherwise fastened thereto. Short bars 131 (Figure 8) are welded to the lower pipe 121. Water is circulated through the loops and through the spout 123 by means of an inlet and outlet connections 133 and 134. If desired, the bars 128, 129 and 130 and the loops 121 may be covered by refractory material, as indicated at 135. The pipe loops 121 and associated bars are secured to the furnace floor by welding the short bars 131 to the studs 136 which are carried by the grid pipes 137, the latter being covered by refractory material 138, as in conventional practice.

Thus, the ring 120 surrounds the slag tap hole 11a and prevents slag from flowing through the hole except at one point, defined by the ring spout 123. The circulation of the cooling water through the connections 133 and 134 and the pipe loops 121 prevents the high temperature of the molten slag from affecting the loops 121 or bars 128, 129 and 130.

The baffle 50a is constructed similarly to the ring 120. The baffle 50a consists of a coiled loop of pipe or conduit having three sections 141, 142 and 143 connected together by bars 144 securely welded to the pipe loops 141, 142 and 143. Inlet and outlet connections 151 and 152 extend through the furnace walls 3a, like the connections 133 and 134, and one leads through the pipe section 141 (Figure 7) around to a return bend 153 (Figure 9) which is welded to the ends of the pipes 141 and 142. The pipe 142 extends around in a spiral, as best shown in Figure 7, in spaced relation with respect to the slag ring 120, except at the end as indicated at 154, where a return bend 155 connects to the loop of pipe 143 which lies above the section 142 and follows the same around to the point where it connects to the other connection 152. A lower bar 157 is welded to the pipe 142 and also to the furnace floor grid, preferably but not necessarily in the manner shown in Figure 8, and the bar 157 is of varying height to permit the baffle to lie level while accommodating the slope of the furnace floor, as shown in Figure 6. The return bend 153 is disposed from the adjacent portion of the baffle by a relatively small amount, as indicated at 160 in Figure 7.

A bar 161 is welded in place between the return bend 153 and the adjacent part of the baffle, providing what might be termed a weir over which the slag from different portions of the furnace flows in entering between the convolutions of the baffle 50a. At this point the various reactions take place which may result in foaming, gassing and the like, but the relatively long distance of flow which this slag is required to follow before it reaches the ring spout sets up a de-gassing pool and provides a sufficient opportunity for all of these reactions to progress to completion before the molten slag reaches the spout 123. The flow of cooling water through the connections 151 and 152 and around the pipe loops 141, 142 and 143 prevents the baffle from being damaged by the high temperature of the molten slag, and if desired, the baffle may be covered by refractory material, although I have found that this is not nec-

sary since some of the slag may freeze on the baffle and act itself as a refractory. In operation, the slag flows continuously around through the baffle 50a and out the ring spout 120. The reactions that take place within the de-gassing pool established by the baffle are hastened by the heat within the furnace itself, and the disposition of the spout 11a in the furnace floor makes it unnecessary to supply slag spout heating means, as in Figure 3. When the boiler is operated but the slag is not used for making mineral wool, the slag drops into a water chamber 165 (Figure 6), but when the slag is to be used for making mineral wool, the water chamber 165 is replaced by a slag runner, such as the construction shown in Figure 1.

As will be apparent, the size of the baffle necessary to set up or establish a de-gassing zone may vary as conditions demand. Usually, it is desirable to determine by experiment the size of pool and rate of flow therethrough which will secure the desired amount of gas removal.

While I have shown and described above preferred constructions and methods of operation, it is to be understood that my invention is not to be limited to the details shown and described above but that, in fact, widely different means may be employed in the practice of the broader aspects of my invention.

What I claim, therefore, and desire to secure by Letters Patent is:

1. The combination with a wet-bottom boiler having a slag tap opening, of means for establishing a degassing zone comprising a slag ring surrounding said opening and having a spout discharging into said opening, a slag baffle of generally spiral formation having one end disposed

against said slag ring adjacent said ring spout and the outer end spaced so as to form a restricted opening through which all slag reaching said slag tap opening must pass, thereby producing a thorough commingling of the portions of the molten slag from different parts of the boiler to provide for the escape of gas from the molten slag before the latter reaches the slag tap opening.

5 2. The combination with a wet-bottom boiler having a slag tap opening, of baffle means defining a space about said tap opening and having an inlet opening remote from said tap opening, said baffle means being arranged so that all

15 of the slag is required to flow through said inlet opening into said space where a pool of the same is formed in which any reaction of the slag that may take place is substantially completed before it flows out of said tap opening.

20 3. In a furnace of the wet-bottom type having a slag tap and utilizing pulverized coal as a fuel, means for segregating a relatively small portion of the slag bottom by two baffles secured to the furnace bottom with the ends con-

25 verging so as to form a slag pool with two restricted openings one of which constitutes an inlet through which all of the slag in the bottom must flow and the other of which discharges through said slag tap, said slag pool being of sufficient length and area as to enable any slag reaction caused by the co-mingling of various portions of the slag from different parts of said slag bottom adjacent said inlet to be substantially completed by the time it flows out of said slag tap.

30 35 CHARLES F. RAMSEYER.
